UNITED STATES PATENT OFFICE

JOHN ADAMS BOLTON, OF TIMPERLEY, ENGLAND

APPARATUS FOR REGULATING THE CONCENTRATION OF SOLUTIONS

Application filed June 6, 1930, Serial No. 459,484, and in Great Britain April 20, 1929.

This invention relates to mercerizing, bleaching or like industrial processes in which a liquor is employed, the concentration or strength of which must be maintained. The method generally adopted at the present time is to provide a supply of concentrated liquor and a control by which an operator may admit same at will, but such methods depend on the care and skill of the operator and are inclined to produce irregular and varying results, as it is well known that such process is very sensitive to any change of concentration of the liquor.

The object of the invention is an improved means to enable such concentration to be maintained and thereby to increase the efficiency or control of the process.

According to the invention, in apparatus for mercerizing, bleaching or like industrial processes in which a liquor is employed, means are provided for automatically maintaining a predetermined concentration or strength of liquor, comprising a tank, means for continuously circulating the liquor through the tank, means for maintaining a constant level of liquor in the tank, a hydrometer in said liquor in the tank and control mechanism operated by the movements of the hydrometer for admitting concentrated liquor to the circulating liquor.

In one example of the invention, as applied to the process of mercerizing fabrics, a pump and strainer are provided for circulating the liquor continuously in the mangle tank, and a control tank is provided in such circuit for the circulation of the liquor positioned after the strainer and just before the pump. Said control tank is provided with means for maintaining a constant level and in the tank is a hydrometer, preferably protected against the effect of eddies from the circulation of the liquor but nevertheless sufficiently exposed to render it immediately sensitive to any change in the "Twaddell" or concentration of the liquor, of which the caustic soda content is being continuously absorbed by the cloth during the mercerizing process. The hydrometer is provided with, or connected to, electric switch contacts so that, when the hydrometer sinks with the weakening of the so-

lution, an electric circuit will be completed which may be employed to open a valve and admit concentrated liquor to the circulating liquor until the concentration has caused the hydrometer to rise and break the said circuit or complete another circuit to close the valve. In this way the concentration may be maintained automatically within quite narrow limits, determined only by the sensitivity of the hydrometer and of the switch mechanism employed therewith. The switch mechanism will preferably be arranged in a sealed or separate compartment so as to remove it from the effects of the liquor, and may be separated therefrom by a flexible diaphragm, such as rubber. Adjustment will also be provided for setting the mechanism to maintain a predetermined "Twaddell" and also for varying the limits of the control, as by raising or lowering the switch mechanism relative to the hydrometer, or by varying the level of the liquor, and the means for effecting such adjustment may have a graduated operating dial.

The control valve may be of the barrel type and a quadrant and solenoid be provided for operating the same, either directly or through a relay circuit connected to the switch mechanism.

When combined with apparatus for cooling the liquor, the additional caustic liquor will preferably be admitted with the cooled liquor as it enters the mangle tank, so that it will be mixed therein and so that the control takes immediate effect. If desired, the control tank may also be positioned at such plate, i. e. after the cooling of the liquor, but before the entry for the fresh liquor, so that with the control of the temperature the control of the hydrometer will be the more accurate and sensitive and the concentration of the liquor reestablished before it enters the mangle tank.

The switch mechanism, operated by the hydrometer, may if desired be such that a proportional control of the admission valve may be obtained varying with the amplitude of the movements of the hydrometer and thus still more effectively maintain the "Twaddell" of the liquor.

The accompanying drawings illustrate a

constructional embodiment of the invention.

Fig. 1 is an elevation with the front of the tank removed.

Fig. 2 is a plan of Fig. 1.

Fig. 3 is a detail sectional elevation of the switch.

Fig. 4 is a diagrammatic illustration of the layout of the several parts of the apparatus of an example of mercerizing plant embodying the elements of the invention.

As illustrated, *a* is a control tank having an inlet *b* shielded by a baffle *c*, the top of which is above the liquid level and which extends nearly to the bottom of the tank. On the side 15 of the tank is an outlet connection *d* having a weir *e* for the purpose of maintaining a constant level in the tank. On another side of the tank and away from both the inlet and outlet but relatively between them is the 20 "Twaddell" regulating mechanism comprising a hydrometer *f* of "Monel metal" supported in a lower guide *g* secured to the side of the tank above the level of the liquid and in an upper adjustable combined guide and contact switch. The tank is divided by a horizontal liquid-tight plate above the lower guide for the hydrometer, for the purpose of 25 protecting the switch and control mechanism from the effects of the fluid. The upper guide 30 comprises a clamping ring *h* secured to a slide *j* running in a guide *k* fixed to the tank wall.

The slide *j* is also formed with a toothed rack *m* engaging a pinion *n*, which latter is 35 mounted on a spindle in the wall of the tank and has at its outer end an operating knob *o* with pointed *p* coacting with a dial *q*.

Details of the clamping ring *h* are shown in Fig. 3, in which are shown an end contact 40 piece *r* secured to the end of the hydrometer, having an electric connecting wire *s* and an annular insertion *t* of insulating material. The upper portion of the end piece *r* above the insulation is slightly enlarged conically for 45 reasons hereafter explained. Within the clamping ring *h* is a vulcanite insulating disc *u* carrying a contact disc *v*. The upper end of the hydrometer is a sliding fit in the insulating disc, which forms a guide therefor, and 50 its movements therein are limited in one direction by a stop pin *w* in the end of the hydrometer and by the tapered head of the end piece of the hydrometer.

In operation, the fluid is pumped into the 55 tank and flows out therefrom over the weir outlet so that a constant level is maintained, the baffle *c* preventing undue turbulence due to the inflow of the liquid. The knob is set to the dial reading of the required "Twaddell" and thereby the upper combined guide and contact switch is raised or lowered to a predetermined position. Should the "Twaddell" of the liquid be too low then the hydrometer will sink in the fluid relative to the 60 upper guide and the upper portion of the end

piece *r* of the hydrometer will make contact with the contact disc *v* held in the clamping ring *h*. This contact completes an electric circuit to operate a valve *x* (see Fig. 4), through suitable solenoid *x* to open the valve admitting concentrated liquor from a tank *y* so as to enter and mix with the liquor in circulation to the mangle tank *z*. The circulating system also comprises a filter *z*¹ and pump *z*².

By providing a series of contacts the switch may be made to open the valve to several positions so that progressive control of the valve is obtainable, giving a more sensitive operation. The switch may be constructed to operate for reducing as well as increasing the "Twaddell" automatically, a supply of diluting water and similar valve mechanism being provided.

The invention is not confined to the particular application above described or to the constructional example given which may be varied without departing from the nature of the invention, for example, although electrical control is preferable as being the most practicable and sensitive, other means might be adopted, also the disposition and arrangement of the circulation system may be varied as required. The invention can be applied direct to the mangle tank, without a circulating system, or with a circulating system, but without temperature control, but the best results are obtainable where the benefit of both temperature and "Twaddell" control are provided.

What I claim is:—

An apparatus for regulating a solution comprising hydrometer means, a tank to receive the solution to be regulated, a hydrometer disposed to be acted upon by the said solution, means for supplying material to the solution, electrical control means therefor comprising an adjustable member having a guide opening through which the hydrometer passes and guiding and limiting the movement of the hydrometer, a slide carrying the adjustable member, guiding means for the slide, and operating means for manually raising and lowering the slide.

In testimony whereof I have signed my name to this specification.

JOHN ADAMS BOLTON.
